UNITED STATES PATENT OFFICE.

ANNA NICODEMUS, OF CHICAGO, ILLINOIS.

BODKIN.

1,149,397.

Specification of Letters Patent. Patented Aug. 10, 1915.

Application filed June 8, 1914. Serial No. 843,616.

To all whom it may concern:

Be it known that I, ANNA NICODEMUS, a citizen of the United States, residing at Chicago, in the county of Cook and State of Illinois, have invented a certain new and useful Improvement in Bodkins, of which the following is a specification.

My invention relates to improvements in bodkins and the like and is illustrated grammatically in one form in the accompanying drawing, wherein—

Figure 1 shows a bodkin in operation; Fig. 2 shows a section along line 2—2 of Fig. 1 on an enlarged scale; and Fig. 3 shows a section along line 3—3 of Fig. 1 on an enlarged scale.

Like parts are indicated by the same number throughout the several figures.

1 is a piece of lingerie or other article 20 which is slotted or apertured at 2, 2 for the passage of the ribbon.

3 is the ribbon or tape which is to be drawn through.

The bodkin is made up of two forwardly 25 converging or inclined wire members 4, 5 joined at one end by a crosspiece 6. The connection between the crosspiece 6 and the wire 4 is substantially a right angle, the connection between the crosspiece 6 and the wire 5 being curved to provide a spring 30 effect. The forward end of the piece 5 is provided with a pin point as at 7 and engages a socket 8, which socket is formed in the end of one arm of a V-shaped part 9 which is carried by the forward end of the wire 4.

It will be evident that, while I have shown 40 in my drawing an operating device, still many changes might be made in size, shape and arrangement of parts without depart-

ing materially from the spirit of my invention. I wish, therefore, that my drawing be regarded as in a sense diagrammatic.

The use and operation of my invention are as follows: Preparatory to using the device the pointed pin is sprung out of the socket and assumes the position shown in dotted lines. This pointed end is then threaded or run through the end of the ribbon as indicated in Fig. 1. The pin is then sprung back into the socket which projects within the pointed end. The V-shaped end of the bodkin is then inserted into the slots in the fabric and fed through in the usual manner. The crosspiece carrying the forward end of the tape thus feeds it smoothly through the fabric without twisting or warping of the tape or ribbon.

I claim:

A bodkin made up of a single piece of 60 wire formed in a loop, having two forwardly converging side members, a cross member tying together the widely separated ends of the side members and arranged substantially at right angles to the center line of 65 the loop, a V-shaped forward extension extending from the two forward ends of the side pieces forwardly to form a blunt point, a socket contained in the wire immediately behind one side of such V-shaped piece, the 70 side member of that side terminating in a point under tension to engage and be held in position in said socket.

In testimony whereof, I affix my signature 75 in the presence of two witnesses this 3rd day of June, 1914.

ANNA NICODEMUS.
